WILKIE HORATIO HOLBY, OF MARTHA, OKLAHOMA, ASSIGNOR OF ONE-HALF TO
R. M. SIMMONS, OF HOBART, OKLAHOMA.

LUBRICANT-FEED.

1,117,847.

Specification of Letters Patent. Patented Nov. 17, 1914.

Application filed August 19, 1913. Serial No. 785,589.

To all whom it may concern:

Be it known that I, WILKIE H. HOLBY, a citizen of the United States, and a resident of the city of Martha, in the county of Jackson and State of Oklahoma, have invented a new and Improved Lubricant-Feed, of which the following is a full, clear, and exact description.

My invention has for its object to provide 10 means for feeding a lubricant to a crank case of an internal combustion engine, the construction being such that the lubricant will be maintained at a pre-determined level in the crank case and the feed will be positive even when the engine is running at a 15 high rate of speed and the lubricant in the crank case is churned by the crank.

The lubricant feed is constructed with a reservoir having a valve and a float with 20 means for maintaining the lubricant at a pre-determined level in the reservoir; communicating means connects the reservoir with a sleeve and within this sleeve there is a tube leaving an oil space between the sleeve 25 and the tube, the tube being secured at one end in an opening in the crank case and having a head at its other end for engaging the outer end of the sleeve for holding the sleeve in position in the direction of the crank case, 30 there being openings in the tube through which the lubricant flows from the sleeve to the interior of the tube and thence to the crank case. In this way the level of the lubricant in the crank case is maintained by 35 the means for maintaining the lubricant at the said pre-determined level in the reservoir. At the outer end of the tube there is a cock for drawing off the lubricant when desired.

40 Additional objects of the invention will appear in the following complete specification in which the preferred form of the invention is disclosed.

In the drawings similar characters of reference indicate corresponding parts in all the views, in which—

Figure 1 is a sectional view on the line 1—1 of Fig. 2 with a portion of the reservoir broken away to show its construction; Fig. 50 2 is a sectional view on the line 2—2 of Fig. 1, and Fig. 3 is a view showing the construction of the tube.

By referring to the drawings, it will be seen that a reservoir 5 is provided, this 55 reservoir being preferably constructed with

a glass wall 6 so that the height of the lubricant contained in the reservoir may be readily seen. Connected with the top of the reservoir 5, there is an inlet 6 having a valve seat 7, a needle valve 8 being provided for 60 coöperating with the valve seat 7 in the customary manner. The upper end 9 of the needle valve 8 is disposed in a guideway 10 in the inlet 6 which holds the needle valve 8 in operative position at all times. The 65 needle valve 8 is provided with two collars 11 which are spaced apart, the arm 12 of the lever 13 being disposed between these collars 11 for operating the needle valve 8. To the other arm 14 of the lever 13 there is 70 articulated a float 15. The bottom of this reservoir 6 communicates by means of a pipe 16 with the interior of a sleeve 17 through the opening 18 in the said sleeve. This sleeve 17 has at its inner end 19 a head 75 20 with an opening 21, the opening 21 being less in diameter than the inner diameter of the central portion of the sleeve 17 so that when the tube 22 is disposed within the sleeve 17 there will be a lubricant space 80 23 between the walls of the sleeve 17 and the tube 22. The tube 22 has a threaded end 24 which meshes in the threaded opening 25 in the bushing 26, this bushing 26 having a threaded neck 27 which is disposed 85 through an opening 28 in the crank case 29, and which is held in position by the nut 30 which meshes with the thread on the neck 27. In this manner the tube 22 is held in 90 position relatively to the crank case 29 and has communication with the interior of the crank case. The sleeve 17 is held in the direction of the bushing 26 by means of the nut or head 31 which engages the outer end 32 of the sleeve 17. There is a gasket 33 between the head 20 and the bushing 26 so that when the head 20 is pressed in the direction of the bushing 26, there will be no leakage between the head 20 and the said bushing. There are openings 34 in the sides 100 of the tube 22 so that the lubricant which flows into the sleeve 17 from the reservoir 5, may flow into the crank case. In the head 31 there is a thread opening 35 in which meshes the threaded end 36 of a cock 37 by 105 which the parts may be readily drained. It will be understood that when the crank case is provided with a bushing 26 held in place by nut 30 and with a cock 37 with its threaded end 36 meshing in the threaded 110

opening in the bushing that the cock may be removed and the tube 22 may be secured with the sleeve 17 in the manner which has been described and that the cock 37 which 5 has been removed from the bushing may then be used to close the outer end of the sleeve 17 at its head 31.

Having thus described my invention, I claim as new and desire to secure by Letters Patent:

1. In a lubricant conveying device, a sleeve adapted to communicate with a source of lubricant supply, a tube of less diameter than the sleeve and disposed within the 15 sleeve with a lubricant space between the walls of the sleeve and the tube, the tube having openings in its walls and having a threaded end for meshing in a threaded opening in a crank case with which the tube 20 is adapted to communicate and a head on the tube for engaging the sleeve for holding the sleeve in the direction of the crank case.
2. In a lubricant conveying device, a sleeve adapted to communicate with a source 25 of lubricant supply, the sleeve having a head at one end with an opening of less diameter than the inner diameter of the body of the sleeve, a tube adapted to communicate with a crank case and disposed within the sleeve fitting the opening and having a threaded end projecting beyond the opening, the central portion of the tube having openings and 30 being spaced from the central portion of the sleeve, a head on the other end of the

tube for engaging the other end of the sleeve 35 and a cock at the said other end of the tube.

3. In a lubricant conveying device, a sleeve adapted to have communication with a source of lubricant supply, the sleeve having 40 a head at one end with an opening of less diameter than the inner diameter of the body of the sleeve, a tube adapted to communicate with a crank case and disposed within the sleeve fitting the opening and having 45 a threaded end projecting beyond the opening, the central portion of the tube having openings and being spaced from the central portion of the sleeve, a head on the other end of the tube for engaging the other end 50 of the sleeve, a cock at the said other end of the tube, a bushing for engaging a side of the crank case about an opening therein, a neck on the bushing for extending through 55 the last mentioned opening, the neck being provided with outer threads, and inner threads with which the threaded end of the tube meshes and a nut normally meshing 60 with the outer threads on the neck for co-operating with the bushing for clamping the bushing around the opening.

In testimony whereof I have signed my name to this specification in the presence of two subscribing witnesses.

WILKIE HORATIO HOLTBY.
